BATHROOM CABINET FOR DOUCHE EQUIPMENT

Gloria Ann Hutchins, Sullivan, Mo.
(3542 Connor Ave., St. John, Mo. 63121)

Filed Dec. 7, 1966, Ser. No. 4,954

Term of patent 14 years

(Cl. D4—3)

FIG. 2

FIG. 3

FIG. 1 is a front elevation of a bathroom cabinet for douche equipment showing my new design.

FIG. 2 is an enlarged front elevation of the cabinet in open condition.

FIG. 3 is a vertical sectional view taken on line 3—3 of FIG. 2.

The broken line disclosure of douche equipment is shown for illustrative purposes only.

I claim:

The ornamental design for a bathroom cabinet for douche equipment, substantially as shown and described.
